UNITED STATES PATENT OFFICE.

HARRY J. VALENTINE, OF HEMPSTEAD, NEW YORK, ASSIGNOR TO WILLIAM VOGEL & BROTHERS, OF BROOKLYN, NEW YORK, A FIRM COMPOSED OF HENRY J. VOGEL, LOUIS H. VOGEL, AND WILLIAM H. VOGEL.

COIN-RECEPTACLE.

SPECIFICATION forming part of Letters Patent No. 746,205, dated December 8, 1903.

Application filed March 26, 1902. Serial No. 100,022. (No model.)

To all whom it may concern:

Be it known that I, HARRY J. VALENTINE, a citizen of the United States of America, and a resident of Hempstead, Nassau county, New York, have invented certain new and useful Improvements in Coin-Receptacles, of which the following is a specification.

The present invention relates to coin-receptacles or money-boxes which are now in common use by savings-banks, life-insurance companies, and other institutions and serving as an auxiliary savings-bank for the collection of money to be deposited. Some of these coin-receptacles consist of a box-body having a removable cover, others having a hinged cover.

Those with removable covers are often objected to, partly because the boxes cannot be open and closed conveniently, partly because the covers are apt to be misplaced, and partly because valuable time is lost in removing the covers of a large number and then replacing them after the coins have been dropped out. The boxes with hinged covers secured by a lock are frequently preferred, because these objections are avoided, and hence my invention resides in the provision of a simple, serviceable, and ornate coin-receptacle of said preferred class, in which a smooth exterior is provided, so that the box may be easily and freely handled, and which may be readily slipped into a coat-pocket. Incidental advantages will appear in the course of the description.

To these ends my invention consists of certain novel features of construction and combinations of parts to be hereinafter described and then claimed.

In the accompanying drawings, Figure 1 is a perspective view of my improved coin-receptacle. Fig. 2 is a transverse section thereof on line 2 2, Fig. 1, the device being closed. Fig. 3 is a similar section, the device being opened; and Fig. 4 is a longitudinal section on line 4 4, Fig. 1.

The metallic box-body A has a hinged metallic cover B, provided with a suitable lock C, the bolt of which may engage a keeper D. Opposite the hinge the top of the box has a coin-receiving slot a, while a pivoted handle E is located adjacent the slot. The corners

of the box-body and cover are rounded, as shown, so as to be unobjectionable when handled and to be slipped easily into a side coat-pocket when desired.

Coin-receptacles of hinged members and locked together usually have projecting hinges, so that a box which is objectionably rough at these points is provided. Also as the top of the box is provided with the coin-slot the hinge or hinges located on the opposite (generally flat) side forming the bottom of the box prevent the box from resting squarely and steady on a flat shelf or table. In the present invention a peculiar hinge-joint is formed, overcoming these objections. For this purpose the cover B is provided at its hinge-joint with integral extending portions b on its rim b', and as the cover is of the same size as the box-body, so that the edges match, the said extending portions will fit into a transverse recess e in the edge of the box-body. Hinge members or plates f f' are riveted or brazed to the inner sides of the box-body and extending portions, respectively, so that a pivot-pin g may pass therethrough and extend across the cut-away portions on the inside of the box-body. The pivot-pin g being located on the inner side of the coin-receptacle and the extending portions b and cut-away portions e being provided, the result is a coin-receptacle with a hinged cover in which the hinge is out of sight when the receptacle is closed and on which there are no rough places or bulges at the hinge-joint outside the receptacle, so that the exposed surfaces of the hinge-jointed sides of the box-body and cover are smooth and flush throughout and serve as the bottom of the receptacle.

As shown, there are two extending portions and two cut-away portions; but it is clear that there may be one of each or more than two. When the receptacle is resting on its smooth exterior hinge-jointed side, the coin-slot is at the top and coins may be readily dropped into the receptacle.

When the receptacle is opened, the extending portions move out of the cut-away portions, leaving openings; but these are entirely closed by the extending portions, which act as doors when the cover is closed and locked.

A strip G, riveted or otherwise secured to the inner side of the edge of the box-body, projects sufficiently beyond the said edge to form a rabbet-groove in which the edge of 5 the cover fits. This strip forms at the same time an obstruction against the insertion of a blade intended to pry the cover open. This strip is preferably cut away or omitted adjacent the hinges.

10 What I claim as new and of my invention is—

In a coin-receptacle, the combination of a box-body having a cut-away portion in one

side, a cover provided with an extending portion fitting snugly in the said cut-away portion, plates secured to the inner sides of the box-body and the extending portions, and a pivot-pin secured beneath the plates, substantially as described.

Signed at Brooklyn, New York, this 21st 15
day of March, 1902.

HARRY J. VALENTINE.
